UNITED STATES PATENT OFFICE.

CHARLES EDMUND FAUTH AND GEORGE DAVID SKAMPER, OF CHICAGO, ILLINOIS.

AUTOMATIC SHEET-MUSIC CORNET.

No. 873,035.

Specification of Letters Patent.

Patented Dec. 10, 1907.

Application filed April 20, 1906. Serial No. 312,869.

To all whom it may concern:

Be it known that we, CHARLES EDMUND FAUTH and GEORGE DAVID SKAMPER, citizens of the United States, residing at Chicago, in the county of Cook and State of Illinois, have invented a new and useful Automatic Sheet-Music Cornet, of which the following is a clear and accurate specification.

Our invention relates to the class of automatic musical instruments which produce every desired melody or other musical piece by the simple performance of certain mechanical functions. We obtain this object by a novel mechanical contrivance which is concealed within the familiar form of a cornet, and as the quality as well as the color of the tone can be made to resemble that of a cornet very closely, a person using and manipulating it skilfully may create the impression of a genuine performance upon it. The power required to operate the device is produced by finger pressure upon the button of a pin, located in the position of and resembling the customary cornet valves, whereby the impression of a true exhibition is greatly strengthened. A bar contains a series of reeds, which are tuned in proper chromatic order. Each reed is located in an orifice and is actuated by wind passing through the latter which causes a metallic tongue to vibrate whereby the sound is produced. The required wind is blown into the mouth piece of the instrument. A music-sheet is passed over the bar by the mechanism, which sheet is provided with corresponding openings whereby the respective orifice containing a tune is periodically covered and uncovered. When uncovered, wind passes through the orifice, actuates a metallic tongue and produces a sound. The tempo or speed at which the succession of sounds may be produced can be regulated mechanically at the will of the person handling the instrument. In our device this is accomplished by a more or less rapid manipulation of the above mentioned button, whereby the power operating the mechanism and controlling its speed can be increased or decreased.

It will be readily apparent that instead of the metallic tongues, other sound producing devices actuated by wind may be employed. It may also be mentioned in this connection that instead of a single melody, harmonies

can be produced upon this instrument, which shows that the musical possibilities of it are not exhausted with the detailed specification as hereinafter set forth. For the purpose of a description it is sufficient, however, to refer to one mode of producing melodies only.

The device is fully illustrated in the accompanying drawings, in which—

Figure 1, is a complete elevation of the uncovered device. Fig. 2 is a plan view, 65 showing the relative position of the various parts. Fig. 3 is a detail of the ratchet attachment whereby the power spring is held under tension. Fig. 4 is an end elevation, showing part of the mechanical movement. 70 Fig. 5 is a sectional elevation at A—A, Fig. 1. Fig. 6 is a perspective view of the bar containing the reeds, partly in section. Fig. 7 is a perspective plan view of the cover, by which the music-sheet is held down slidingly 75 upon the bar. Fig. 8, is a detail of the spring housing, showing pawl for ratchet wheel; Fig. 9, is a detail of the mechanism by which the power is produced in combination with the detail shown in Fig. 8; Fig. 10, 80 is an exterior view of the complete instrument; Fig. 11, is a perspective view of the complete instrument, partly opened and showing interior arrangement; Fig. 12, is a detail of the spool containing the music-sheet. Fig. 13, is a perspective detail showing the method of transmitting the power. Fig. 14 is a horizontal section of the spring housing and the gears adjacent thereto.

Like characters refer to like parts throughout the various views.

Referring to the drawings, *a* represents the casing within which the device is mounted. This casing is divided into two parts, of which *a'* is the bottom box and *a''* the cover. Both parts are hinged together and can be closed by spring clip *a''*, as shown in Fig. 11.

The wind is conducted into the bar containing the reeds through wind pipe *B*; pipe *b* receives the sound from sound chamber *b'* and conducts it to the sound transmitter *b''*.

c and *c'* represent valve buttons, of which only *c'* is useful while the other two are ornamental and riveted to the casing simply for the purpose of completing the exterior appearance of the instrument.

The power contrivance which moves the music sheet will be best understood from

drawings Figs. 1 and 2 in which *a* is the casting, *c'* the useful and *c* the ornamental buttons. *c'* is fastened to a pin 1 by which the power mechanism is actuated. Fig. 13. 5 This pin 1 is pivoted at point *p* to arm 2 and at point *p'* to arm 3. Arm 2 is attached to toothed segment 2', while arm 3 is a part of spring housing 3', wherein spring 4 is attached with one end to axle 5 and with the 10 other end to the housing 3' as shown in Fig. 8. Arm 2 and its segment 2' are rigidly mounted upon axle 6, while axle 5 carries segmental gear wheel 5' which is fastened to axle 5 in line with toothed segment 2' where- 15 by gear connection between the two is established as in Fig. 13. Spring housing 3' carries pawl 7 and pawl spring 7'. Gear wheel 8 is provided at its hub with ratchet wheel 8' and 8''. This gear wheel is slipped upon 20 axle 5 in such a way that ratchet wheel 8' connects with pawl 7. Spur gear 5' carries on its inner side pawl 5'' and pawl spring 5'', which pawl connects with ratchet wheel 8'' when all the parts are slipped upon axle 5 in 25 their proper position. All parts carried by axle 5 *i. e.* spring housing 3', gear wheel 8 with its two ratchet wheels 8' and 8'', and spur gear 5' are rotatably mounted upon the same, so that each one may revolve freely in 30 the direction of the force moving it. Both axles are journaled in frame *f* and *f'*, as shown in Figs. 1 and 2. *f'* is riveted to the side frames *f''* in such a way that the proper distance between *f* and *f'* for the free move- 35 ment of the above mentioned axles is main- tained. A ratchet wheel 9 is fastened to axle 5 outwardly of frame plate *f*. A pawl 9' and spring 9'' acts in correspondence with it, as shown in detail Fig. 3. This attach- 40 ment serves the purpose of holding spring 4 in spring barrel 3' under any desired tension, before finger pressure is exerted upon but- ton *c'* for the purpose of pressing down pin 1. The double ratchet movement, as shown 45 in Fig. 13, provides uninterrupted move- ment of the gear wheel 8 and thereby of the music-sheet, as will be seen later. The power movement operates as follows:—Pin 1 is pressed down by finger pressure, whereby 50 spring housing 3' is rotated around axle 5 a corresponding distance. As pawl 7 is fastened to spring housing 3', it will be carried with it; in so doing it glides down upon the ratchet teeth of ratchet wheel 8'. During 55 this movement the tension of spring 4 is increased, so that when the finger pressure is removed spring housing 3' will revolve upon axle 5 in the direction of the spring tension, whereby pawl 7 engages with ratchet wheel 8' and turns gear wheel 8 in the direction of the arrow as indicated in Fig. 1. It is evi- 60 dent that during the interval of time re- quired to increase the tension of spring 4, another movement is needed to rotate the 65 gear wheel 8. This is accomplished by seg-

ment 2' in connection with spur gear 5' and pawl 5'', which latter engages with ratchet wheel 8'' of gear wheel 8 and rotates it during the full downward stroke of pin 1. In other words gear wheel 8 is rotated during the 70 down-stroke of pin 1 by segment 2', spur gear 5' and pawl 5'' and when the finger pressure is removed from button *c'* it is rotated in the same direction by the tension of spring 4 in connection with pawl 7 and 75 ratchet wheel 8''. Axle 10 is also journaled in frame plate *f* and *f'*. Fastened upon it is pinion 10' and worm gear 10''. Outwardly of frame *f*, fly-wheel 11 is secured to axle 10 by a pin 11' which passes through its hub 11''. This fly wheel serves the purpose of steadyng the speed of mechanical move- 80 ment. Pinion 10' is in gear connection with gear-wheel 8 which drives it. Worm gear 10'' is in gear connection with worm 12' of 85 lug 12, which latter is journaled in lug *f''* and in lever 23 at a right angle to axle 10.

Pinion 12' is fastened to axle 12 outwardly of frame plate *f''* where it transmits the move- 90 ment to gear wheel 14, which is secured to shaft 15 of spool 15'. Shaft 15 is journaled in frame plates *f''* and *f'* and during the rotating movement of spool 15' the music sheet is gradually unwound from spool 16' and wound around spool 15'. Spool 16' is se- 95 cured to shaft 16 and journaled in bosses 17 and 17', which are fastened to frame plates *f''*. Pinion 16'' is rigidly mounted upon pin 18 outwardly of frame plate *f''*. Pin 18 is rotatably secured in boss 17 by shoulder 18' on one side and pinion 16'' on the other. The 100 music sheet is hooked upon hook 22' of spool 16' and is wound on said spool before the latter is inserted into its place in the device, and its connection with pinion 16'' and pin 18 is made easily interchangeable by providing axle 16 with a pin 16''' at the end adjacent to pinion 16''. Pin 18 is provided with a slot 18'' which receives pin 16'''. At the other end of spool 16', a pin 19 containing a bore, 110 wherein axle 16 is journaled, passes through boss 17' which is forced against the spool by spring 19''. When spool 16' is to be removed, it is only necessary to force back pin 19 against spring 19'' whereby pin 16''' will be 115 disengaged from slot 18'', whereupon the spool may be removed.

Between the two spools, reed bar 20 is located and is provided with orifices 20' and with a metallic reed or tongue 20'' for each orifice. The music-sheet 21 is passed over the bar and is fastened by means of its loop 21' to hook 22, which is placed midways between the two end flanges of spool 15'. When the mechanical movement is set into 125 action, the music-sheet is drawn by it over bar 20 and wound around spool 15'. When the end of the music-sheet 21 is reached and all of it is wound around spool 15', it is necessary to rewind it upon spool 16'. This is 130

done by reversing the mechanical movement, see Fig. 4. It will be recalled that the power is transmitted to axle 12 by means of worm 12' and worm gear 10'. At the end nearest 5 to the worm this axle is journaled in lug f^3 , on the other end it rests in slot 13 and is journaled in the end of lever 23, which lever is pivoted at point p^2 in frame f^2 . This lever maintains proper gear-connection between 10 pinion 12' and gear wheel 14. When music-sheet 21 is to be rewound upon spool 16', lever 23 is pressed down and pinion 12' is swung upwardly in slot 13 passing into gear connection with gear wheel 24, which latter 15 is fastened to axle 24' having its journals in frame plates f^4 and f^2 . It is then only necessary to manipulate pin 1 rapidly which increases the speed of the mechanical contrivance and rewinds music sheet 21 upon 20 spool 16' in a short time.

When a melody is to be produced, it is necessary to pass the music sheet sufficiently tight over bar 20 so as to avoid loss of wind between the surface of the bar and the music-sheet, as all the wind is required to pass 25 through such slots 21' as may be used to uncover the desired orifice containing the wanted tune. A simple means whereby this result is effected is shown in Figs. 5 and 30 7. The music-sheet 21, which is being unwound from spool 16' to spool 15', passes over the curvature of reed-bar 20, whereby its slots 21' periodically uncover the orifices 20' to produce the desired tune. The sound 35 chamber b' is a part of cover a^2 ; it is provided with two flanges 25 to which is fastened a celluloid plate 25', which latter is provided with slots 25' to correspond with the orifices 20' in the reed bar. A strip of felt 26 is 40 placed on both ends of the bar—see Fig. 2,—which allows the music-sheet 21 to pass through the small space between celluloid plate 25' and the curved reed-bar 20, without binding it. When cover a^2 is closed, the 45 sound chamber b' with its celluloid plate 25' presses the music-sheet gently against the surface of the bar, so that no wind is lost between the surface of the bar and the music-sheet. During action the wind which is 50 blown into the mouth piece passes into the reed bar 20, vibrates the metallic tongue 20' which produces the sound, and passes out through orifice 20'.

It will be seen from the above description 55 that the device is of so compact a nature that it may be placed in a comparatively small instrument as for instance a cornet. Its mechanical movements differ essentially from the devices ordinarily employed, as the large 60 spring barrel which is usually the source of power and which requires an intricate clock-work mechanism, is entirely omitted: The power is created by the use of finger pressure upon a valve button, which greatly simplifies 65 the mechanical contrivance lightens the de-

vice materially and gives the performance upon the instrument the air of genuineness. Similar devices may be placed in similar instruments and operated in a like manner; in that way it is possible to assemble a complete band using various instruments all of which are provided with devices constructed in accordance with the spirit and within the scope of our invention.

Having thus fully described our invention, 75 what we claim as new and desire to secure by Letters Patent is:

1. In a device of the class described the combination with a mouth tube of a reed bar supported thereon, a perforated sheet fitting 80 closely on said bar, a reciprocating pin and mechanism connecting said pin with said sheet and adapted to advance the sheet across the bar at each movement of the pin.

2. In a device of the class described the 85 combination with a tube of a casing supported thereon, a reed bar in said casing, a perforated sheet adapted to move across said bar, a reciprocating pin in said casing and means 90 connecting said pin with said sheet adapted to advance the sheet when the pin moves in either direction.

3. In a device of the class described the combination with a coiled mouth tube of a 95 casing supported in the coil thereof, a reed bar in said casing, reeds therein, a perforated sheet adapted to move across said bar, a reciprocating push pin protruding from said casing, means operated thereby adapted to advance the sheet across the bar at both the 100 inward and outward movement of said pin and a reversing mechanism adapted to reverse the movement of the sheet on further operation of the pin.

4. The combination with a mouth tube, of 105 a casing supported thereon, a reed bar in said casing, in open communication with said tube, a plurality of reeds therein, a perforated sheet, a roll on each side of said bar adapted to carry said sheet, a gear on each roll, a pinion adapted to mesh with either gear, a shaft on said pinion, a reciprocating push pin protruding from said casing and means connecting said pin with said shaft adapted to advance the sheet across the bar at the movement of said pin in either direction.

5. In a device of the class described the combination with a coiled wind tube of a casing connected therewith, a hollow bar in said casing in open communication with said tube, reeds in said bar, a spool on each side of the bar, a perforated sheet thereon adapted to lie in close contact with the bar, a gear on one of said rolls, a pinion in mesh therewith, a shaft on said pinion, a gear operatively connected with said shaft, ratchets on said gear, a spur gear and a spring housing supported adjacent said gear, a pawl on each of the same adapted to engage said ratchets, a segment gear in engagement with the spur gear, 125 130

- an arm operatively engaged with said segment gear and housing and a push pin connected with said arm and adapted to advance the sheet at both the inward and outward movement thereof.
6. In a device of the class described the combination with a coiled wind tube, of a casing supported thereon, a hollow bar in said casing into which said tube opens, reeds 10 in said bar, a spool journaled in the casing at each side of said bar, a reciprocating push pin, means adapted to transform the reciprocating motion of the pin into a direct motion and a train of gears connecting said means 15 with said spools and adapted to advance the sheet at each movement of the pin.
7. In a device of the class described the combination with a casing of an apertured reed bar therein, a sound chamber adjacent 20 said bar, a wind tube opening into said bar and from said chamber, a perforated sheet, a reciprocating push pin in said casing and means actuated thereby adapted to advance

the sheet across the bar at each movement of the pin.

25

8. In a device of the class described the combination with a casing of an apertured reed bar therein, a sound chamber in said casing, a wind tube opening into said bar and from said chamber, a spool journaled at each side of said bar, a perforated sheet thereon, adapted to be moved across the bar in close contact therewith, a reciprocating push pin in said casing, means adapted to transform the reciprocating motion of said pin into a direct motion and means actuated thereby adapted to advance the sheet at each movement of the pin.
